UNITED STATES PATENT OFFICE.

OTTO G. WERNER, OF NEWARK, NEW YORK, ASSIGNOR OF ONE-HALF TO FRANK W. GILBERT, OF NEWARK, NEW YORK.

FORCED-DRAFT PAN STRUCTURE.

Application filed September 16, 1925. Serial No. 56,727.

The present invention relates to an improved pan structure for supporting grates adapted for use with a forced draft and has for its principal object to generally improve 5 upon the valve structure used with the pan.

Another very important object of the invention is to provide an improved valve structure which will remain closed under the accumulated pressure which may occur by 10 coal dust or other fuel caking on the grate and preventing the circulation of the forced draft so that said accumulative pressure may break up said cake formed on the grate but which will open should an explosion 15 take place by the ignition of accumulative gases in the furnace.

Another important object of the invention is to provide a valve structure which is capable of being easily and quickly disassembled when desired for the purpose of 20 cleaning out the pan.

With the above and numerous other objects in view as will appear as the description proceeds, the invention resides in certain 25 novel features of construction, and in the combination and arrangement of parts as will be hereinafter more fully described and claimed.

In the drawing:—

30 Figure 1 is a side elevation of the improved pan embodying the features of my invention.

Figure 2 is a bottom plan view thereof.

35 Figure 3 is an enlarged detail section taken through one of the valves.

Referring to the drawing in detail, it will be seen that 5 designates the pan or bowl adapted to support a grate such as is disclosed clearly in my pending application 40 bearing Serial Number 37,737, filed June 17, 1925. A pipe 6 depends centrally from the bottom of the pan 5 and has a reduced terminal 7 over which may be received one end of an elbow 8 leading from a suitable 45 source of forced draft. To each side of the pipe 6 there is disposed a valve structure depending from the bottom of the pan. These valve structures are identical in form and a detailed description of one 50 will suffice for both. Referring to one of the valve structures in detail it will be seen that numeral 9 designates a depending cylinder having its upper end fixed to a depending flange 10 formed integral with the 55 bottom 11 of the pan 5 and disposed around

the opening 12. A cap 13 is constructed with an upwardly disposed annular flange forming a cylinder 14 slidable over the exterior surface of the cylinder 9. A bar 15 extends diametrically across the cap 13 on 60 the under surface thereof and is fixed thereto in any suitable manner. This bar 15 extends beyond the edge of the cap 13 terminating in curved extensions 16. A pair of hooks 17 depend from the bottom 11 one 65 above each extension 16. Springs 18 are gageable with the hooks 17 and extensions 16 for holding the cap 13 in abutment with the bottom edge of the cylinder 9. These springs 18 have sufficient tension to prevent 70 the opening of the cap from the cylinder 9 under ordinary accumulative pressure within the pan 5 or within the furnace so that should the grate become clogged so that the air may not pass therethrough the pressure 75 may accumulate from the forced draft source to such an extent as to unclog the grate without opening the valves. However, should an explosion take place within the 80 furnace because of the ignition of accumulative gases, as frequently occurs, the pressure caused by such explosion will be sufficient to overcome the tensions of the springs 18 and allow the cap 13 to unseat 85 sufficiently to relieve said pressure. The accumulative pressure spoken of above may unseat the cap 13 from the bottom edge of the cylinder 9 but nevertheless no air may escape because of the close fit of the cylindrical flange 14 in the cylinder 9. 90

The present embodiment of this invention has been disclosed merely by way of example since in actual practice it attains the features of advantage enumerated as desirable 95 in the statement of the invention and the above description. It will be apparent that numerous changes in the details of construction may be resorted to without departing from the spirit or scope of the invention as hereinafter claimed or sacrificing any of its 100 advantages.

Having thus described my invention what I claim as new is:—

1. In combination, a forced draft grate supporting pan, an outlet formed in said pan, a closure enclosing said outlet and having means permitting limited movement of the closure without uncovering the outlet, and means normally holding said closure closed under ordinary accumulative pressure 105 110

within the pan and permitting said limited movement and also adapted to allow the unseating of said closure under explosive pressure for opening the outlet.

- 5 2. In combination, a forced draft grate supporting pan, a cylinder depending from said pan, a second cylinder telescopically associated with the first cylinder, a cap formed on said second cylinder, and a spring means associated with the cap to normally hold it closed on the lower end of the cylinder and of such a tension to prevent the cylindrical flange from being forced from the cylinder under ordinary accumulative pressure but allowing the cylindrical flange to be forced from the cylinder under explosive pressure.
- 10 3. In combination, a forced draft grate supporting pan, a cylinder depending from said pan, a cap closable over the lower end of said cylinder and provided with a cylindrical flange telescopically associated with the cylinder, and springs normally holding said cap seated on the lower end of said cylinder and preventing the removal of the cylindrical flange from the cylinder under ordinary accumulative pressure but allowing the removal of said cylindrical flange from the cylinder under explosive pressure.
- 15 4. In combination, a forced draft grate supporting pan, a cylinder extending from the pan, a cap on the outer end of the cylin-

der, a cylindrical flange formed on the cap and telescopically associated with the cylinder, a bar extending diametrically across the cap and terminating in curved extensions beyond the edge of the cap, hooks mounted on the pan, and springs detachably engaged with said curved extensions, and of such a tension to normally hold the cap seated on the outer end of the cylinder and to prevent the removal of the cylindrical flange from the cylinder under accumulative pressure but allowing the removal of the cap and flange from the cylinder under explosive pressure.

5. In combination, a forced draft grate supporting pan, a cylinder extending from the pan, a second cylinder telescopically associated with the first cylinder, a cap on the second cylinder closable over the outer end of the first cylinder, and spring means associated with the cap to normally hold it seated on the outer end of the first cylinder and of such a tension as to prevent the removal of the second cylinder from the first cylinder under ordinary accumulative pressure but allowing the removal of the second cylinder from the first cylinder under explosive pressure.

In testimony whereof I affix my signature.

OTTO G. WERNER.
